(57) **CLAIM**

The ornamental design for a container nipple connector, as shown and described.

DESCRIPTION

FIG. 1 is a top perspective view of the container nipple connector showing the new design;

FIG. 2 is a front elevation view thereof, the rear elevation view being a mirror image thereof;

FIG. 3 is a left elevation view thereof, the right elevation being a mirror image thereof; and,

FIG. 4 is a top plan view thereof, the bottom plan view comprising unclaimed subject matter bounded by a circular boundary shown in FIG. 3.

1 Claim, 4 Drawing Sheets

FIG. 1

FIG. 2

FIG. 3

FIG. 4
